AUTOMOBILE RADIO ANTENNA ORNAMENT

Edward B. Caldwell, Akron, Ohio

Application July 11, 1958, Serial No. 51,737

Term of patent 7 years

(Cl. D14—6)

FIG. 1

FIG. 2

FIG. 3

Fig. 1 is a front elevational view of an automobile radio antenna ornament showing my new design;

Fig. 2 is a side view thereof; and

Fig. 3 is a cross-section taken on line 3—3 of Fig. 1.

I claim:

The ornamental design for an automobile radio antenna ornament, substantially as shown.
